(57) **CLAIM**

The ornamental design for a tire tread depth indicator, as shown and described.

DESCRIPTION

FIG. 1 is a front perspective view of a tire tread depth indicator of the present application;

FIG. 2 is a front elevation view thereof;

FIG. 2A is a front elevation view indicating cross-sections **5-11** thereof;

FIG. 3 is a bottom perspective view thereof;

FIG. 4 is an environmental view thereof;

FIG. 5 is a top detail view at cross-section **5** thereof;

FIG. 6 is a top detail view at cross-section **6** thereof;

FIG. 7 is a top detail view at cross-section **7** thereof;

FIG. 8 is a top detail view at cross-section **8** thereof;

FIG. 9 is a top detail view at cross-section **9** thereof;

FIG. 10 is a top detail view at cross-section **10**; and,

FIG. 11 is a top detail view at cross-section **11** thereof. In the drawings, the broken lines depict environmental subject matter only and form no part of the claimed design.
